UNITED STATES PATENT OFFICE.

HENRY W. WHITE, OF NEW ORLEANS, LOUISIANA.

SHINGLE FASTENER.

Application filed January 2, 1925. Serial No. 189.

To all whom it may concern:

Be it known that I, HENRY W. WHITE, a citizen of the United States, residing at New Orleans, in the parish of Orleans and

5 State of Louisiana, have invented certain new and useful Improvements in Shingle Fasteners; and I do hereby declare the following to be a full, clear, and exact description of the invention, such as will enable 10 others skilled in the art to which it appertains to make and use the same.

This invention relates to wire shingle fastening means, and has for its object to provide a device of this kind which will be 15 simple in construction, comparatively inexpensive to manufacture, and more certain in action than those which have been heretofore proposed.

With these and other objects in view, the 20 invention consists in the novel details of construction more fully hereinafter disclosed and particularly pointed out in the claims.

Referring to the accompanying drawings, forming a part of this specification in which 25 like numerals designate like parts in all the views,—

Figure 1 is a diagrammatic view of a portion of a shingled roof with this invention applied thereto;

30 Figure 2 is a cross sectional view of the parts shown in Fig. 1;

Figure 3 is a diagrammatic plan view showing how this invention may be applied to rectangular or polygonal shaped shingles;

35 Figure 4 is a perspective view of the shingle fastener detached from the roof;

Figure 5 is a sectional view taken on the line 5—5 of Fig. 4; and

40 Figure 6 is a diagrammatic view of the end portion of a somewhat modified form of shingle fastener.

1 indicates ordinary rectangular shingles laid upon a roof in overlapped relations as 45 indicated, 2 the upturned overlying ends of a shingle fastener provided with a main body portion 3 and holding loops 4 as indicated. Through the loops 4 are passed the nails 5 to hold the fastener firmly in place, as will be clear from Figs. 1, 2 and 5. In other words, as will be clear from Figs. 1 and 2, the main body portion 3 of the fastener is laid down flat upon the lower layer 50 of shingles 1 so that the loops 4 will overlie adjacent shingles separated by a crack 6. Nails 5 are then driven through the lower

layer of shingles 1 and through the loops 4 into the sheathing 7 below said shingles so as to hold the fastener firmly in place with its upturned ends 2 ready to receive shingles of 60 the upper layer, as shown in the drawings. After the main body portion 3 of the fastener is thus secured to the lower layer of shingles, the upper layer of shingles 1 is slipped under the overlying hooked end portions 2 of the fastener and said hooked portions 2 may be given a blow with a hammer which will cause the same to snugly hold the shingles 1 in place.

In the somewhat modified form of hooked end shown in Fig. 6, the hook portion 2 is given a curved shape, as indicated at 9, so that when the extreme end is struck by a hammer it will sink into the shingle 1 at the point 10, as indicated. In other words, the hooked end 2 is preferably so cut off as to leave a sharp point which may readily enter the shingle when struck by a hammer, although the perfectly straight form of hooked end is also useful when mashed down upon the shingles, and especially when the shingles are made of paper, felt or of other composition material.

Fig. 3 illustrates how the main body portion 3 may overlie overlapping portions of 85 a pair of rectangular shingles 11 and 12, have nails driven through the looped portions 4, and how the overlying hooked ends 2 may receive a third overlapping shingle 90 13. In other words, this shingle fastener is adapted not only for the ordinary form of wooden shingles shown in Fig. 1, but it is also adapted for the various kinds and shapes of asphalt shingles, as will be clear 95 from Fig. 3.

It is an important feature of this invention that the loops are at right angles to the main body portion 3 of the shingle and that the wire is not bent through a 100 complete circle of 360 degrees so as to provide overlapped portions of the wire in the fastener at the loop portions thereof. Should such a construction be adopted, there would be two thicknesses of wire separating the upper and lower tiers of shingles, where- 105 as when the loop is not completely closed, as is illustrated in Fig. 4, only a single thickness of wire separates the upper and lower shingles, all as will be clear from 110 Fig. 5.

Further, it is an important feature of the invention that there is a separate and

distinct fastener for each individual shingle, so that the portions 15 of the hooks 2 may extend around the two side edges of each shingle and thus hold them firmly in position down next to the lower tier of shingles. In other words, as is well known to builders, a great deal of damage is done to shingle roofs due to the fact that the wind gets up under the lower ends and edges of the shingles, lifts the same and tears them from their positions on the roof. If one attempts to prevent this by driving nails in close to the lower ends or to the edges of the shingles, these nails are liable to split the shingles, and if the material is not very strong the wind is liable to tear the shingles from the nails, so that such fastening means are very unsatisfactory. On the other hand, with a shingle fastener such as that illustrated in Fig. 4, nails passing through the loops 4 can be driven through the lower tier of the shingles and through the strongest portions of the material of the shingles without any danger at all of splitting or otherwise injuring the shingles, while the hooks 2 can be so positioned as to hug tightly the extreme lower side edges very near the extreme lower ends of the shingles and thus hold them firmly in position against all lifting actions of windstorms, as will be clear from Fig. 1 of the drawings. Especially are the lower ends of the shingles held firmly in position when the hooked portions 2 are mashed down firmly against the surfaces of the upper tier of shingles.

What is claimed is:—

1. The herein described shingle fastener made from a single piece of wire having a main body portion provided with an open

ended loop adapted to overlie a shingle, and with hooked end portions disposed in the same plane said plane being at right angles to the plane of said loop.

2. The herein described shingle fastener made from a single piece of wire and of a length equal to the width of the portion of an upper shingle to be fastened and provided with a main body portion adapted to overlie the surfaces of two abutting lower shingles, said main body portion provided with a plurality of open ended loops disposed in one of the planes of said main body portion and also adapted to overlie said surfaces and to receive nails driven through said surfaces, and said main body portion further provided at each end portion with turned over hooks disposed in another plane of said main body portion and substantially at right angles to the plane of said loops.

3. The herein described shingle fastener made from a single piece of wire bent to form a plurality of open ended loops adapted to lie flat upon the surfaces of a pair of lower shingles disposed adjacent each other and to receive nails driven through said shingles, said wire at each end outside of said loops also bent to form open hook portions disposed in a plane substantially at right angles to said loops adapted to receive the side edges of an upper shingle overlying said lower shingles, and said hook portions provided with a curved portion near the extreme ends of the wire to facilitate the driving of said ends into the material of said upper shingle.

In testimony whereof I affix my signature.

HENRY W. WHITE.
